Primary Examiner — Brett Miller*Assistant Examiner* — Nader Abadir(74) *Attorney, Agent, or Firm* — Hodgson Russ LLP(57) **CLAIM**

The ornamental design for beverageware as shown and described.

DESCRIPTION

FIG. 1 is a perspective view of beverageware showing my new design;

FIG. 2 is a right side elevation view thereof;

FIG. 3 is a left side elevation view thereof;

FIG. 4 is a rear elevation view thereof;

FIG. 5 is a front elevation view thereof; and,

FIG. 6 is a top plan view thereof.

The broken lines illustrate portions of the beverageware that form no part of the claimed design.

1 Claim, 6 Drawing Sheets
